UNITED STATES PATENT OFFICE.

HENRY HERMANI, OF BALTIMORE, MARYLAND, ASSIGNOR TO TIN DECORATING COMPANY, OF BALTIMORE, MARYLAND, A CORPORATION OF MARYLAND.

APPARATUS FOR APPLYING HINGE-PINTLES TO BOX-PART BLANKS.

1,267,409.

Specification of Letters Patent.

Patented May 28, 1918.

Application filed August 4, 1917. Serial No. 184,514.

To all whom it may concern:

Be it known that I, HENRY HERMANI, a citizen of the United States, residing at Baltimore, in the county of Baltimore and State of Maryland, have invented new and useful Improvements in Apparatus for Applying Hinge-Pintles to Box-Part Blanks, of which the following is a specification.

This invention relates to apparatus for applying hinge pintles to box part blanks, and has particular relation to apparatus for producing the pintle-receiving configurations of the blank and applying the pintle to such configurations by a sequence of automatic operations.

Metallic boxes of the hinged type generally employ a pintle structure on one of the box parts. In order to provide for approximate uniformity of product and low cost of manufacture, it is desirable that the pintle application be produced automatically. Attempts have been made to produce this result in various ways, a satisfactory solution of the problems involved being that disclosed 25 in the patent to Alexander W. George, No. 1,117,030, in which the pintle has one end introduced beneath an ear of the box part a distance greater than that required in the completed product, after which the other end is positioned in alignment with the entrance to its ear and the pintle moved backward so as to insert the latter end. This general method enables the pintle to be inserted in an efficient manner, and is employed in the present apparatus.

To provide for pintle applying by this method, it is essential that the box part to which the pintle is to be applied, have its pintle-receiving configuration produced on the blank prior to its being placed in position for pintle applying, it being understood, of course, that the ears beneath which the pintle is to be secured must be present in the box part before the pintle can be initially inserted. The treatment of the box part blank to produce this configuration has generally been provided in separate apparatus, the two types of apparatus being entirely independent.

Each of these operations—the initial manipulation for preparing the blank and subsequent pintle application—practically requires that the box part be positioned on a supporting form at the time when the operation takes place, this form conforming more

or less to the configuration of the interior of the walls of the box part, these operations taking place on one of these walls. In other words, the form is of the male type with respect to the box part blank. Consequently, in each of these operations, it is necessary that the box part be first placed in position on the form, then operated upon to produce the desired result, and then removed from the form. Obviously, this involves a more or less accurate positioning of the box part, and, so far as I am aware, this positioning and removal has heretofore been provided manually. As a result, the capacity of the apparatus is more or less limited by the ability of the operator to provide the positioning and removal operations, and the uniformity of product is also more or less dependent upon the careful attention of the operator in positioning the box part blank. Consequently the success of the general operation is more or less dependent on the manual dexterity of the operator; attempts at high speed tend to increase the number of defective structures, it being readily understood that not only is substantial accuracy required in the formation of the ears in order that the pintle may be properly inserted, but the completed structure must be substantially accurate in order that the complementary box part—also generally made by die structures—will not only assemble with the pintle carrying part, but will, when assembled, provide for a proper mating relation with the walls of the box part in closing.

The present apparatus is designed not only to produce the pintle-receiving configuration and apply the pintle in the same machine, but to provide these operations automatically and in an automatic sequence through the use of a feed mechanism which will provide the successive positionings and removals in proper manner and in timed sequence, meeting the various problems involved by the use of simple and efficient mechanism, thereby eliminating substantially all manual positioning and removing operations. At the same time the apparatus is designed for large capacity thereby increasing the output and decreasing the cost of production of the completed box part.

To these and other ends, therefore, the nature of which will be readily understood as the invention is hereinafter disclosed, said

invention consists in the improved construction and combination of parts hereinafter fully described, illustrated in the accompanying drawings, and more particularly 5 pointed out in the appended claims.

In the accompanying drawings, in which similar reference characters indicate similar parts in each of the views:

Figure 1 is a front elevation of one embodiment of apparatus for carrying out the principles of the invention, parts being broken away to show underlying elements.

Fig. 22 is a perspective view showing a box part blank before introduction to the apparatus.

Fig. 23 is a similar view showing the form 60 of the box part upon the completion of the apparatus operation.

To explain the general character of the present invention, comparison may be made between the box part blank shown in Fig. 65 22 and the completed box part shown in Fig.

23, these views showing one form of box part which may be operated upon by the present apparatus, being one embodiment of a general type of metallic box part which is adapted to be hingedly connected to a 70 complementary member to complete a commodity-receiving box. As will be seen in Fig. 22, the blank consists of the bottom (or top, depending upon which is to carry the pintle) x and walls x' forming an annular 75 flange which is substantially imperforate. This is a common form of blank readily produced by dies.

As shown in Fig. 23, one of the walls x' has been operated upon to produce ears y 80 and a match-scratching surface w , a pintle p being inserted beneath the ears y , thus producing a box part to which the complementary member can be hinged in the usual manner.

Before entering into a detail description of the particular embodiment of apparatus disclosed herein, a brief statement of the sequence of operations is given.

The blanks are introduced into the general 90 feeding mechanism by a traveling conveyer on which the blanks are placed with the open side of successive blanks in the same direction, the conveyer bringing the blanks successively into contact with a stop member 95

which is arranged to act somewhat on the order of an escapement to permit the blanks to move forward individually at proper timed intervals. This permits the supply of blanks to be collected on the conveyer, succeeding blanks being in contact, the stop 100 permitting the blanks to escape one at a time. The escaping blank is introduced into a carrier channel within which it is advanced by an advancing mechanism which 105

positions the blank at a predetermined point in this channel. The channel with its blank is then shifted laterally to place the blank within the operating zone of a reciprocating advancing instrumentality which acts to advance the blank in the channel a distance sufficient to carry it out of the path of the 110 succeeding blank, after which the channel is returned to its initial position, carrying the shifted blank with it, thus permitting 115

the introduction of the succeeding blank into its initial position in the channel, the advancing instrumentality returning to its initial position after the channel has carried the blank out of the operative path of movement of the advancing instrumentality. The 120 succeeding blank is then introduced—thus placing two blanks within the channel—after which the channel again moves transversely to carry both positioned blanks 125 within the operating zone of the advancing instrumentality. The latter then advances, carrying both blanks forward, thus carrying the advance blank to a position opposite the form and mechanism for preparing the wall 130

- of the blank for insertion of the pintle, the succeeding blank being advanced and placed in the position which has been vacated by the first blank, thus again leaving the entrance to the channel open to receive the third blank. The channel is then returned to its initial or normal position, placing the blank on the form, after which the advancing instrumentality again returns. The preparation of the blank takes place during the period when the third blank is being received in the channel and while the advancing instrumentality is returning, the movement of the latter shifting the position of the blank on the form in order to permit its ready removal when the channel is again shifted laterally, the third blank then being in position. After the channel has been shifted to remove the blank from this form, the advancing instrumentality is operated to advance the three blanks which have been successively positioned in the channel, the first blank passing to a position opposite the pintle-applying form, the second blank opposite the blank preparing form and the third blank advanced out of the entrance to the channel. Therefore when the channel returns to its normal position, it will place the first blank—now prepared to receive the pintle—on the pintle-applying form, the second blank will be positioned on the blank preparing form, and the entrance to the channel will be clear for the succeeding blank. In this position of the carrier, the second blank will be operated on to produce the pintle-receiving ears, etc., a pintle will be applied to the first blank, and a fourth blank introduced into the entrance to the channel, thus placing a blank at each of the four stations within the channel. The pintle application is completed while the first blank is positioned on the form, after which the channel is again moved transversely, removing the first and second blanks from their respective forms, the remaining blanks being shifted as explained, and the advancing instrumentality brought into action to advance the several positioned blanks, this movement carrying the completed blank out of the channel and positioning the second blank on the pintle-applying form, and the third blank on the blank preparing form. As will be seen, this provides a step-by-step advancing movement to a blank successively to each of the stations, each operation being similar, the carrier having a cycle which carries it laterally and then back, these operations being spaced by periods of dwell, while the advancing instrumentality reciprocates in directions parallel to the length of the channel, the reciprocations taking place during periods of dwell of the carrier, the movements of carrier and instrumentality being non-concurrent. Throughout the travel of the blank, it remains in the carrier channel, and the successive operations described are such (assuming the proper introduction of a blank whenever the entrance to the channel is unobstructed) that each cycle of back and forth movements of the carrier completes a box part, the blank preparing and pintle-applying operations taking place concurrently, a new blank being introduced for each completed part discharged from the apparatus. Hence the capacity of the machine is practically controlled by the length of time required to apply the pintle and the time required to advance the blank from one station to the next. The latter time is comparatively small for the reason that the shifting movements of the channel and of the advancing instrumentality can be made with more or less rapidity.
- As will be understood, no manual manipulation is required, other than that which might be necessary in keeping the conveyer supplied with blanks. If the present apparatus is so positioned that the blanks delivered by a blank-forming apparatus be discharged on to the conveyer, manual feeding can be eliminated.
- For convenience in description, I indicate the several stations as A, B, C and D, station A being at the entrance to the channel, station C being the station at which the blank is prepared for pintle-applying, and station D the pintle-applying station. No work is performed at station B, this station being designed more particularly to provide the supply for station C without complicating the general operation by attempting to introduce a blank and properly locate it on the die at station C at one operation, this introduction and positioning being divided into two steps, the first step being the introduction and initial positioning of the blank, thereby requiring a minimum amount of time to complete the initial positioning action—a time within the limits of that required at the working stations—leaving the delivery of the blank to station C as a separate operation. This particular arrangement locates four blanks in the channel while the working stations are operating, but the presence of this number of blanks does not affect the general operation.
- A description of the invention will more or less follow the successive station operations.
- As shown more particularly in Figs. 1 and 2, 30 designates a general supporting frame on which the operating parts are mounted, 31 indicating the drive shaft, driven from a suitable power source.
- Referring more particularly to Figs. 4 to 10, 32 designates an element—shown in detail in Fig. 8—mounted on a table portion 30a of the frame. Element 32 comprises a vertical plate member 33 to which is secured

an elongated member 34, the latter carrying a strip-like member 34^a which forms the bottom of a blank feeding channel, the channel being completed by a plate member 35 (Fig. 4) secured to elongated member 34.

The channel between members 34 and 35 is adapted to receive the upper flight of an endless conveyer 36 (Figs. 1 and 2), this flight being located above member 34^a, the 10 conveyer being mounted on suitable rolls 37 and 38, roll 37 being carried by a shaft operatively driven from the drive shaft by a drive connection 38'. Members 34 and 35 are of any desired length; conveyer 36 is 15 preferably designed to be constantly driven. As the channel formed between members 34 and 35 is adapted to receive the blanks and form the supply for the general operations, it will be understood that the length of this 20 channel is preferably sufficient to permit the operator to maintain a sufficient number of blanks therein to supply the machine.

Conveyer 36 is adapted to advance the blanks positioned in the channel into cooperative relation with a stop member 39 carried by member 33, said stop member being pivotally connected, as at 39^a to guide 40 (Fig. 11), members 33 and 34 having slots 33^a and 34^b respectively to permit the angular extension 39^b to project into the path of travel of the advancing blanks, a spring 39^c serving to normally retain the tapered end of the member in position to intersect the blank travel path as shown, for instance, 25 in Figs. 4 to 6. As shown in these views, member 39 normally contacts with the advance of the rear wall of the blank, the major portion of the blank which is being held being in advance of the stop member, the 30 latter being spaced from the advance end of the active conveyer flight a distance to permit of the blank being positioned in this manner and yet remain on the conveyer. Obviously, the succeeding blanks will be held 35 against advance movement so long as stop member 39 holds the advance blank from movement. The blanks which are successively positioned on the conveyer will be advanced until each contacts with the preceding blank, the positioned and held blanks remaining stationary while the conveyer continues its movement. When, however, member 39 is moved on its pivot to withdraw its tapered end from the feeding channels, the blanks positioned on the conveyer will advance in the channel until stop member 39 is again made active. The normal position of stop member 39 is such as to intersect the travel path of the blanks and is 40 intermittently withdrawn from its normal position for a sufficient length of time to permit the contacting walls of the blank being held and the succeeding blank to pass by the tapered end of the member, the latter then 45 returning to normal position to contact with

the rear wall of this succeeding blank. Withdrawal movement of member 39 is provided by the following mechanism:

41 designates a slide mounted in guide 40 (Figs. 11 and 12) said slide carrying a pawl 42, pivoted at 42^a to permit of a limited oscillatory movement, said pawl carrying a finger 43 at its advance end, said finger projecting laterally through a slot 33^b formed in member 33. Slide 41 is adapted to be reciprocated by a bell crank lever 44 (Fig. 1) connected to pawl 42 by a link 44^a, lever 44 being adapted to be rocked by suitable mechanism operated by drive shaft 31, as for instance a crank arm 45 and a link 45^a connecting the crank arm and bell crank lever, movements of the crank arm, through the connections described, causing slide 41 to be reciprocated in guide 40.

Stop member 39 carries an element 46 having a downwardly projecting portion 46^a adapted to cooperate with an upwardly extending projection 47^a of an element 47 carried on pawl 42. Projecting portions 46^a and 47^a (which may be in reversed relation) 50 are adapted to function more or less as cam members, these projections having configurations approximately as shown in Figs. 4 to 7 and operating in the following manner:

The advance position of pawl 42 is shown 55 in Figs. 4 and 5, at which time finger 43 is at the advance end of slot 33^b. At the proper time, slide 41 is moved rearwardly through the connections indicated, to the position shown in Fig. 6. As link 44^a is connected 60 directly to the pawl, the latter will be initially rocked to withdraw finger 43. Pawl 42 completes its movement in this direction with the parts in this position, projections 47^a and 46^a passing free during this movement. At the beginning of the return movement of the slide, pawl 42 will be rocked in the opposite direction, so that during such return movement the outer face of projection 47^a will contact with the inner face of projection 46^a, as shown for instance in Fig. 7, the result being that projection 46^a will be 70 moved outward during the time required for these contacting faces to pass by each other. Since projection 46^a is practically carried by 75 stop member 39, this outward movement will cause member 39 to be rocked on its pivot to provide withdrawal movement of the tapered end of said member. As soon as projection 47^a passes out of contact with projection 46^a, spring 39^c will return member 39 to its normal position. This period of withdrawal of member 39, though short, is sufficient to permit the contacting walls of the two blanks to pass by the end of the stop 80 member, thus freeing the advance blank and placing the stop member in position to stop the movement of the succeeding blank.

Finger 43 is designed more particularly to positively advance the released blank, this 85

inger, which is adapted to project through slot 34^c in member 34 during the return travel of pawl 42, projecting into the blank in rear of the advance wall of the released blank (Fig. 7), so that as the pawl continues its advance movement to the position shown in Fig. 4, it will advance the released blank to the position shown in said Fig. 4, moving the blank to a position where its advance 10 face is in proximity to or contacts with a stationary projection 33^c carried by member 33. This advance movement of the blank carries the latter into a channel formed in a blank carrier 48 shown more particularly in detail in Fig. 9—projection 33^c extending into the channel at this time—the blank coming to rest at this point, this resting point being indicated as station A.

For purposes of explaining the movements of the blanks through the several stations, four successive blanks will be indicated respectively at *d*, *c*, *b* and *a* in the order of their introduction to station A. Hence the blank thus introduced is indicated 25 in Fig. 4 as *d*.

The blank carrier 48 shown in Fig. 9 is formed of a pair of parallel plate members 48^a and 48^b spaced apart by the bottom member 48^c, this structure forming a channel 30 having an open top and ends. Carrier 48 has a length to include the four stations at which the blank is successively positioned, this carrier having slides 48^d adapted to operate with suitable guides on table 30^c, the 35 arrangement being such as to permit of reciprocation of the carrier transversely to the direction of length of the channel and of the travel of the blank therethrough. The reciprocating movements of the carrier are 40 provided by an oscillatory shaft 49 operatively connected to slides 48^d through link connections 49^a and 49^b, shaft 49 being moved by the action of a cam 50, driven by shaft 31, through the movements of an element 51 and arm 52, the latter being carried by shaft 49, element 51 having one end cooperating with cam 50 and its other end connected to arm 52. For safety purposes in the operation of the apparatus, element 51 is 45 built up to permit of more or less yielding in its direction of length in the presence of excessive pressure in apparatus operation, this forming one of the safety features adapted to take care of any abnormal conditions which may arise in the general operation.

As shown in Fig. 4, the normal position of carrier 48 is with its members 48^a and 48^b in longitudinal alinement with members 34 and 35, thus bringing the channel of the carrier in longitudinal alinement with the conveyer channel heretofore described, this being the position of the carrier when the blank is being introduced. Although not essential, it is 5 preferred that carrier 48 and members 34

and 35 have opposing end configurations more or less interengaged, as for instance is shown in Figs. 8 and 9, thus tending to prevent undesired movements of either of these parts and presenting a smooth wall effect.

Cam 50 is arranged to shift carrier 48 from the position shown in Fig. 4 to that shown in Fig. 5 and return, the shifting movements being comparatively rapid and of short duration, the carrier dwelling in each of these positions to permit operations on the blanks to take place therein. When in the normal position of Figs. 4 and 7, the blanks are in position to be operated upon, this being the blank-working position of the carrier. Shifting of the carrier to the position shown in Fig. 5 is for the purpose of advancing the blanks contained within the carrier to the succeeding stations, this advancing operation being provided by a reciprocating advancing instrumentality indicated generally at 53 and shown more particularly in detail in Fig. 10, the movements of this instrumentality being at right angles to the direction of movement of the carrier 90 and parallel to the direction of length of the carrier channel. Instrumentality 53 is located at one side of the carrier, element 33 at the opposite side.

Advancing instrumentality 53 includes two members 54 and 55, member 54 being slidably mounted in member 55, said members, however, being adapted to normally travel in unison, being operatively connected by a yieldable element 56 carried by member 55 and projecting into member 54. Yieldable element 56 is designed as a safety element to permit relative movement of members 54 and 55 under abnormal conditions, the element being designed to cause the travel in unison under normal conditions. Member 55, which may be considered as a slide member, is mounted on a suitable stationary guide 56^a at the top of the table.

Reciprocation of the advancing instrumentality is provided by a pivoted lever 58, the movements of which are controlled by a cam 59 on drive shaft 31, lever 58 having its opposite end connected to slide member 55 through adjustable connection 60 mounted on pin 55^a of member 55 (Fig. 1).

Member 54 is preferably provided with four projections 54^a, 54^b, 54^c and 54^d, these projections extending on substantially the same horizontal plane and being spaced apart in the direction of length of member 54 a distance substantially equal to the length of the blank, the distance being such as to provide a comparatively loose fit of a blank between adjacent projections during the operation of the apparatus. These projections extend into a slot 48^c of member 48 when the carrier is in its normal position, the length of the projections being preferably such as not to extend into the channel 130

of the carrier in this position, as shown more particularly in Figs. 4 and 7. When, however, carrier 48 is shifted from its normal position, member 48^a moves over these projections a distance sufficient to cause the latter to intersect the carrier channel, as shown in Fig. 5, in which member 55 is shown in its rear position.

It may be noted that when member 55 is in its rear position, projection 54^b will practically oppose projection 33^c of member 33, while projection 54^c will oppose projection 33^d of said member 33, as shown in Figs. 4 and 5.

When, therefore, blank *d* was positioned at station A, it was located in alignment with the space between projections 54^a and 54^b. Hence, when the carrier is shifted to its opposite position, blank *d*, while remaining in the carrier channel, is shifted into this space. Consequently, when instrumentality 53 is advanced by the action of cam 50, thereby advancing the projections of member 54 a distance equal to the distance between the center lines of adjacent projections, blank *d* will be advanced in the carrier channel to a position opposite the space between projections 33^c and 33^d of member 33, as shown by blank *d* in Fig. 5. Instrumentality 53 dwells in this position, and during this period of dwell carrier 48 is returned to its normal position, thus carrying the shifted blank *d* into the space between projections 33^c and 33^d, this position of the blank representing station B.

After the carrier has thus returned, instrumentality 53 returns to its rear position, the movement of the carrier having taken the blanks which may be in the carrier channel out of the path of travel of the projections of member 54.

This cycle of operations of the carrier has resulted in transferring blank *d* from station A to station B, leaving station A empty to receive the succeeding blank, indicated at *c*, which is introduced to this station while the carrier is in this position in the same manner as heretofore explained in respect to blank *d*.

The succeeding shifting movement of carrier 48 from its normal position locates the shifted blank *d* between projections 54^b and 54^c and at the same time positions blank *c* between projections 54^a and 54^b. The advance movement of instrumentality 53 then advances both blanks, positioning blank *c* opposite station B and blank *d* opposite the blank preparing station C into which blank *d* passes when carrier 48 returns to its normal position, blank *c* passing to station B, station A being empty to receive the succeeding blank, the general cycle being completed by the return of instrumentality 53 to its rear position.

The blank preparing or manipulating

mechanism by means of which ears *y* and match-scratching surface *w* are produced, is shown more particularly in Figs. 1, 13, and 14, in which 61 indicates a form which functions as a die member and is removably secured to a bracket 62 suitably supported on table 30^a. Form 61 has its front portion of a general peripheral configuration approximating that of the interior of the walls of the blank, the vertical length of this portion of the form being somewhat less than the distance between the top and bottom walls of the blank. The top of the form is provided with a pair of projections 61^a (Fig. 5) and a more or less serrated portion 61^b, projections 61^a providing the die configuration for the formation of ears *y*, portion 61^b being a die configuration effective in producing the match-scratching surface.

Form 61 is positioned at a point where the blank is free to advance under the action of instrumentality 53 to a position opposite this form, this taking place, as heretofore explained, while carrier 48 is out of its normal position. However, the return movement of the carrier to its normal position carries this blank on to form 61, the latter acting as an anvil of a die press structure. Since the top surface of the form carries projections, it is necessary that the blank be raised in order that its upper wall may clear projections 61^a while the blank is being located on the form. This raising movement of the blank is provided by mechanism now to be described and shown more particularly in Figs. 13, 14 and 16.

Pivottally supported on the carrier is a member 63 (Fig. 16) having its advance end U-shaped and slotted to removably receive a pair of headed pins 63^a, these pins extending upwardly through member 48^c of the carrier into the carrier channel (Figs. 13 and 14). The opposite end of member 63 is provided with a roller 63^b which is located in the slot of a cam member 64 carried by slide member 55 (Fig. 10), the slot of cam member 64 having its opposite ends—64^a—lowered with respect to the intermediate portion 64^b of the slot. When roller 63^b is located at either end 64^a of the cam slot, member 63 will be so positioned as to project pins 63^a into the carrier channel a distance sufficient to raise the upper wall of the blank above the top of projections 61^a; when roller 63^b is in the intermediate portion 64^b of the slot, the pins will be withdrawn from the channel permitting the blank to be seated on the form or on carrier member 48^c at the bottom of the channel.

Cam plate 64, being positively connected to instrumentality 53, reciprocates with the latter. On the other hand, member 63, sup-

ported by carrier 48 is held against movement longitudinally of the carrier being movable with the latter during its back and forth movements. Hence, the movements 5 of cam plate 64 will actuate member 63 to provide the pin projection and retraction at predetermined times. For instance, with instrumentality 53 in its rear position, pins 63^a will project into the channel, roller 63^b being in the advance end 64^a of the cam slot (Fig. 1), the blank in the carrier in this position being raised. As instrumentality 53 advances, it carries the blank from this position, advancing the succeeding 10 blank toward this position. During this movement roller 63^b passes into the intermediate portion 64^b of the slot and retracts pins 63^a, the result being that the advance blank drops on to the bottom of the carrier 15 channel and advances on said bottom, while the succeeding blank is simply moved along on this bottom to this position. As instrumentality 53 approaches the end of its advance movement, roller 63^b passes into the 20 rear end 64^a of the slot, causing pins 63^a to be projected into the slot, and since the advancing rear blank is then in position over both pins, the blank is readily raised and its advance movement completed while in 25 raised position. Carrier 48 is then returned to normal position—instrumentality 53 remaining at rest in its advance position during this return movement—after which instrumentality 53 moves rearward, again 30 withdrawing pins 63^a from the carrier channel through the action of intermediate portion 64^b of the slot, the pins remaining withdrawn until instrumentality 53 approaches its rear position thus again projecting the 35 pins into the channel.

Since member 63 is shiftable with the carrier, roller 63^b is of a length sufficient to be operative in the cam slot in either position.

The die manipulation on the blank is provided while the pins are retracted, retraction of the pins after the carrier has moved inward to locate the upper wall of the blank over projections 61^a, permitting the blank to lower and rest upon these projections. 45 While in this position, the die press operation brings the complementary die structure into operation to produce the desired configuration, this mechanism being as follows:

63 designates the vertical reciprocating 50 head of a die press, the head being operated from drive shaft 31, this head carrying a die 55 removably secured to a block 65^a. This die is shown in detail in Fig. 15, comprising a supporting member 66 having a recess 66^a to receive the die, the latter being preferably 60 sectional in form and comprising the main die member 67 having a recess 67^a to receive die element 68, and an additional recess 67^b to receive die element 69. The main 65 die member is provided with the groove con-

figurations 67^c which are complementary to projections 61^a of die 61 in the formation of ears y.

Die element 68 carries a pair of projections 68^a which substantially align with 70 grooves 67^c, projections 68^a, however, being located between said grooves. Projections 68^a are adapted to cooperate with projections 61^a in providing the necessary slotted condition of the blank to provide for the 75 open ends of ears y. In addition, these projections 68^a are operative to depress the wall of the blank at the entrance to each ear, projections 61^a and 68^a, in operation, producing a configuration of the top wall of the 80 box substantially such as that indicated in Figs. 17 and 18, thus producing an entrance to each ear of a sufficient size for the purpose without, however, requiring extensive ear projection, this arrangement being provided 85 to facilitate the insertion of the pintle as presently described.

Die element 68 has a face complementary to face 61^b of the anvil or form die to produce the match-scratching surface on the 90 wall of the blank. Obviously, where it is not desired to provide the match-scratching surface, the die faces for producing this surface may be omitted, this surface being more or less of a convenience and not essential in 95 the pintle-applying operation.

When, therefore, the blank is located on projections 61^a, as heretofore pointed out, the movements of head 65 bring the several operating faces of the die carried by this 100 movable head into contact with the wall and force the blank downwardly in producing the blank configuration, the movable die then being withdrawn as is usual in die press constructions. The time required to produce 105 this configuration is short and provides complete die operation within the time during which roller 63^b in traveling in the intermediate portion 64^b of the cam slot, pins 63^a therefore being out of the path of the blank 110 while the latter is being moved downward under the die action. Since the die action places projection 61^a in the indentations of the blank, it is essential that the blank be raised from this position before carrier 115 movement to withdraw the blank again takes place, and this raising of the blank for this purpose is provided by the change in position of roller 63^b as instrumentality 53 approaches its rear position.

As a result of these operations at station C, the completion of the cycle of movement of instrumentality 53 leaves the die-produced structure of the blank above the plane of projections 61^a, freeing the blank from 125 any restraint against withdrawal movement, so that when the carrier again moves away from its normal position, this blank is free to move off of form 61 and into the space between projections 54^c and 54^d, thereby po- 130

sitioning the blank at a point where the succeeding advance of instrumentality 58 will carry this blank to a position opposite station D, the remaining blanks being correspondingly advanced, as heretofore described.

Upon the succeeding return movement of the carrier, the blank positioned opposite station D is moved into said station and on 10 to supporting form 70 of the pintle-applying mechanism, the succeeding blanks being positioned in stations C and B respectively.

As shown more particularly in Figs. 17 to 20, die 70, on its upper face, is provided 15 with a recess 70^a of suitable length, this recess being located below the ear configuration produced on the blank in station C. 71 indicates a slideable member suitably supported on form 70 and having an arm 71^a 20 extending through the form, member 71 having a hook end 71^b, said member 71 being normally located at one extreme of its movement (Figs. 17 and 18) in which position end 71^b is located beyond the ear configuration, as shown in these views. The 25 operation of member 71 will be presently described, but it may be noted that this member acts to shift the pintle to complete the pintle-inserting movement, and may also 30 serve as a stop to limit the advance movement of the pintle wire, although this is not essential.

The general cycle of pintle positioning operations is as follows: After the blank has 35 been positioned, a wire feeding mechanism is made active to introduce the advance end of the wire through the opening beneath the rear ear of the blank (Fig. 17); the pintle may be preformed and introduced as a unit, 40 but it is preferred to practically provide the pintle-length during the operation by cutting the pintle from a length of wire, which may, for instance, be supplied from a roll, and this particular type of wire supply is 45 disclosed in the drawings. After the advance end of the wire is introduced, a vertically reciprocating member is brought into operation to cut the wire at the proper point and move the cut end of the pintle 50 downward into a position in alignment with the opening of the advance ear of the blank (Fig. 18), and while in this position, member 71 is moved out of its normal position, the hook end 71^b contacting with the previously inserted end of the pintle and, pushing 55 the pintle ahead during the hook advancing movement, positions the advance end of the pintle beneath the advance ear (Fig. 19), thus inserting the pintle with 60 the pintle ends extending beneath the ears and the intermediate portion exposed. As will be understood, the operation provides for inserting one end of the pintle a distance greater than that required in the final

pintle position, positioning the uninserted 65 end of the pintle opposite the entrance to the other ear, and then shifting the pintle in the opposite direction, this being the general idea disclosed in the patent to George heretofore referred to. The mechanisms 70 for producing this cycle of operations will now be described:

The pintle forming wire, indicated at *r* 75 is supplied from a suitable source, being introduced between a pair of feed rolls 72 and 72^a mounted on a bracket 30^b of the frame, roll 72 having a gear connection with an advancing mechanism, roll 72^a being an idler adjustably mounted in bracket 30^b.

The advancing mechanism for the wire 80 comprises a shaft 73 carrying gear 73^a forming the drive for roll 72, said shaft also having a ratchet 73^b (Figs. 1, 2 and 3). Loosely mounted on shaft 73 is a bell crank lever 74 having one of its arms provided with a 85 pawl 74^a which co-operates with ratchet 73^b. The opposite arm of lever 74 carries a crank pin 74^b extending into an elongated slot 75^a of a link 75 pivotally connected to a link 75^b pivoted to one end of an arm 76, the opposite end of which is pivotally mounted at 90 76^a. Arm 76 carries a roll 77^a which co-operates with a cam 77 mounted on drive shaft 31.

Under normal operations, roll 72 will be 95 intermittently rotated to advance the wire through the action of the link connections which, moving vertically, will permit crank pin 74^b to move downward with link 75, permitting pawl 74^a to ratchet over the 100 teeth of ratchet 73^b, the return movement of link 75 drawing pin 74^b upwardly and thus causing ratchet 73^b to be advanced through the action of pawl 74^a, the parts being so arranged that the advance movement of the ratchet will feed the amount of wire needed for the pintle. 105

In order that no difficulty will be had through feed of wire in case no blank is being positioned to receive the pintle, I preferably employ a safety device which acts to prevent lever 74 from moving during the downward travel of link 75, link 75 being movable downwardly while pin 74^b remains stationary, slot 75^a permitting link 75 to move 110 while pin 74^b remains stationary, return movement of link 75 obviously having no effect in advancing ratchet 73^b. This control is provided through the operations of an arm 78 having one end connected with lever 74, and 115 having its opposite end formed with a hook 78^a adapted to be engaged by the hook-shaped end 79^a of a pivoted lever 79, the opposite end of which is connected to a link 79^b which connects the lever with an arm 80^a 120 carried by a shaft 80, said shaft carrying a finger 80^b located in the path of travel of a blank advancing from a position opposite 125

station C to that opposite station D, this mechanism being more particularly shown in Fig. 1. Arm 78 extends through a bracket arm 78^b (Fig. 3) a spring 78^c being mounted on arm 78 beneath the bracket and tending to move arm 78 downward, said spring thereby forming an element adapted to retain crank pin 74^b at the bottom of slot 75^a during movements of link 75. The parts 10 are so arranged that upon completion of the advance of ratchet 73^b, hook 78^a will be engaged by the hook-shaped end 79^a as shown in Fig. 1, finger 80^b extending downward at this time. Should the succeeding operation 15 of instrumentality 53 fail to advance a blank into contact with finger 80^b, the latter will not be moved and hence the engagement of the hook-shaped ends 78^a and 79^a will not be disturbed, the succeeding movement 20 of link 75 thus having no effect on roll 72. When, however, instrumentality 53 properly advances a blank from station C, the advance end of the blank contacts with finger 80^b and moves shaft 80 which, 25 through connections 80^a and 79^b, rocks lever 79 and moves end 79^a out of engagement with end 78^a, leaving arm 78 free to move downward and thus permit pin 74^b to follow the downward movement of link 75.

30 Wire *r* is passed through suitable straightening rolls 81 and between rolls 82 into a guide 83 which extends over the top of form 70. This guide is shown more particularly in Fig. 17 as in the form of a holder 83^a and 35 a guiding member 83^b through which the advance end of the wire is delivered, member 83^b having its passageway of a size to permit the free movement of the wire therethrough and at the same time prevent material swaying or other movements of the projected portion of the wire.

40 As will be seen, the wire advancing means is preferably arranged at an angle to the horizontal, the angle being such that the advancing wire will enter the opening to the rear ear of the blank; as shown in Fig. 17, a guide 83^c being arranged to correct any slight inaccuracy of movement of the advance end of the wire and directing such 45 advance end into this opening, it being understood that during this advance movement member 71 is at or practically approaching its normal position shown in Fig. 17 and 18, the wire feed movement being provided by the upward movement of link 75. This places the wire in substantially the position shown in Fig. 17 in which the rear end of the pintle (the advance end of the wire) has been inserted into the interior 55 of the blank beyond the position which this end occupies when the pintle has been completely inserted, while the remainder of the pintle is still connected to the wire. The succeeding operation cuts the

wire and locates it in the position shown in Fig. 18, this being provided by the following mechanism:

5 Mounted on block 65^a of head 65 is a member 84 shown more particularly in Fig. 21, this member having a recess 84^a at one side, 70 said recess being adapted to receive a cutting member 85, the lower edge of which practically extends in the plane of the lower end of member 84. The lower end of members 84 and 85 are slotted, as at 84^b and 85^a 75 respectively, to form a guide for the wire, the bottom of slot 85^a forming a cutting edge coöperating with the exposed end of member 83^b to sever the wire at the desired point. Member 84 is also provided with a vertically extending opening 84^c leading to an opening 65^b in block 65^a, said openings being adapted to receive a plunger 86 which normally projects below the bottom plane of member 84, as shown in Fig. 17. Block 85 65^a carries a cap member 87 in substantial alignment with opening 65^b, plunger 86 also extending through cap 87, said plunger having a flange 86^a between which and the bottom of the cap is mounted a spring 86^b. 90

After the advance end of the wire (the rear end of the pintle) has been inserted, downward movement of head 65 carries members 84 and 85 downwardly. Plunger 86 first contacts with the wire and moves 95 inwardly, thereby compressing spring 86^b, the wire passing into slots 85^a and 84^b as the head continues its travel. When the bottom of slot 85^a contacts with the wire, the continued movement of the head provides a 100 shearing action on the wire, thus relieving plunger 86 from restraint and permitting spring 86^b to expand and cause plunger 86 to drive the severed end of the pintle downwardly into position opposite the entrance 105 to the advance ear, as shown in Fig. 18, slots 84^b and 85^a serving to guide this end of the pintle during its downward movement under the action of the plunger, the plunger holding the pintle in proper position opposite the entrance to the ear.

110 While in this position, member 71 is made active to cause the hook end 71^b to contact with the rear end of the pintle and push the pintle forward. Since the advance end of the pintle is practically at the entrance to the advance ear, such pushing or advancing movement of member 71 will cause this advance end of the pintle to enter the ear, the rear end of the pintle at the same time being 120 advanced until it is located under the rear ear, placing the parts in the position shown in Fig. 19 and completing the pintle-applying operation, producing the structure shown in Fig. 23.

125 Upon the next movement of the carrier from its normal position, the completed blank will be moved off of form 70 into the

space in advance of projection 54^a, so that the succeeding advance movement of instrumentality 53 will carry this completed blank practically out of the carrier channel, depending on the length of the channel beyond station D. In the form shown in the drawings, the advance movement of instrumentality 53 will advance the completed box to a position where it may fall out of the channel and be collected in suitable manner.

The movements of members 71 are provided by a cam 71^c coöperating with a lever 71^a connected to member 71 by link 71^b.

As heretofore pointed out, the blank during its advance through the various stations, is retained in the channel of carrier 48. Since, however, the positions of the blanks in stations C and D are such that the supporting forms extend into the blank in either station, carrier 48 has its member 48^b provided with openings 48^f and 48^g, these openings being divided by a part 48^h which, as shown in Fig. 4, is located to move between dies 61 and 70. Like in stations A and B, member 48^b is arranged to shift the blanks from stations C and D, a suitable number of projections 48ⁱ being provided on opposite sides of each of openings 48^f and 48^g to provide the necessary structure in rear of the blank to cause the blank to move with the carrier, projections 48ⁱ extending into recesses 61^c of form 61 and 70^b of form 70 as shown in Fig. 17, so that while provision is made for the entrance of these forms into the blanks, the latter are still retained within the channel of the carrier 48.

Since the moving elements above the blank in each of stations C and D are carried by block 65^a, it will be readily seen that the operations are concurrent in said stations. Since the apparatus is designed to introduce a blank each time the carrier returns to its normal position, thus locating a blank at each of stations A, B, C and D, the introduced blanks advancing step by step through these stations, it will be readily understood that the apparatus requires but little, if any, manual manipulation of the blanks; any blank manipulation would be the introduction of the blank to the conveyer structure, the succeeding operations being automatic.

Owing to the fact that the various manipulations are distributed through various stations and the amount of manipulation on a blank at a single station is comparatively small and of short duration, it will be obvious that the apparatus may be operated at comparatively high speed with a resultant large capacity and comparatively low cost of production of the completed box part.

Other advantages will be apparent. For instance, the various operating parts are of a type which involve no intricate mechanical movements, etc., the construction and operation of the several elements being simple

and therefore not liable to be readily damaged under normal operations. And various safety features are employed—some of which have been described—for the purpose of taking care of difficulties which might possibly occur through defective blanks or accidental wrong positioning of a blank. Should there be any failure in feeding of blanks to station D, either by accident or when the supply is exhausted, or at the beginning of apparatus operation (at which time the various stations are empty and no blank reaches station D until it has passed through the other stations) no feed of wire can take place; since operation of the remaining parts can provide no material damaging conditions, it will be readily understood that the apparatus will be operated efficiently and at a minimum cost, especially since the positioning of blanks is had with substantial accuracy.

Obviously, by the use of changed forms, dies, etc., boxes of various sizes and shapes can be manipulated, and it is to be understood that adjustability of parts, change of forms and dies, change in size of parts, etc., are all contemplated to meet individual conditions of use.

While I have herein shown and described a preferred arrangement and combination of parts, it will be readily understood that changes and modifications therein may be required or desired to meet the various exigencies of this or other uses, and I desire to be understood as reserving the right to make any and all such changes and modifications as may be required or desired in so far as the same may fall within the spirit and scope of the invention as expressed in the accompanying claims when broadly construed.

Having thus described my invention, what I claim as new, is:

1. In apparatus for applying pintles to box parts and in combination, a shiftable carrier for supporting the box part blank, and means for successively preparing the blank to receive the pintle and for positioning the pintle in such prepared blank while the blank is so supported, a positioned pintle being of substantially similar cross-section throughout its length.

2. In apparatus for applying pintles to box parts and in combination, a shiftable carrier for supporting the box part blank, means for successively preparing the blank to receive the pintle and for positioning the pintle in such prepared blank while the blank is so supported, a positioned pintle being of substantially similar cross-section throughout its length, and means for moving the blank relative to its support to locate it in operative position for the successive operations.

3. In apparatus for applying pintles to

- box parts and in combination, pintle-applying mechanism operative to provide endwise movements of the pintle during pintle applying operation, mechanism for preparing the box part blank to receive the pintle, and blank feeding means for delivering the blank to said mechanisms in predetermined succession.
4. In apparatus for applying pintles to box parts and in combination, pintle-applying mechanism, mechanism for preparing the box part blank to receive the pintle, and blank feeding means for delivering the blank to said mechanisms in predetermined succession, said blank preparing means including a form having projections, and means controlled by movements of said blank feeding means for positioning the blank relative to such projections.
5. In apparatus for applying separate pintle elements to a box part and in combination, a box part blank preparing station, a pintle-applying station, wherein the blank and pintle are assembled by relative movements in the direction of length of the pintle, mechanisms operative at the respective stations, and means for advancing a blank successively through said stations.
6. In apparatus for applying pintles to a box part and in combination, a box part blank preparing station wherein a blank is prepared with completed pintle-receiving ears, a pintle-applying station, mechanisms operative at the respective stations, and means for advancing a blank successively through said stations, by a step-by-step movement.
7. In apparatus for applying pintles to a box part and in combination, a box part blank preparing station, a pintle-applying station, mechanisms operative at the respective stations, and means for advancing a blank successively through said stations, said feeding means including a shiftable carrier for supporting the blank during its travel through the stations.
8. In apparatus for applying pintles to a box part and in combination, a box part blank preparing station, a pintle-applying station, mechanisms operative at the respective stations, and means for advancing a blank successively through said stations, said feeding means including a shiftable carrier for supporting the blank during its travel through the stations, and means for advancing the supported blank by a step-by-step movement.
9. In apparatus for applying pintles to box parts and in combination, pintle-applying mechanism adapted to insert pintles by endwise movement of the pintle, mechanism for preparing the box part blank to receive the pintle, and blank feeding means for delivering a succession of blanks to said mech-
- anism, said blank feeding means being operative to position successive blanks concurrently in said mechanisms.
10. In apparatus for applying pintles to box parts and in combination, pintle-applying mechanism adapted to insert pintles by endwise movement of the pintle, mechanism for preparing the box part blank to receive the pintle, and blank feeding means for delivering a succession of blanks to said mechanism, said blank feeding means being operative to position successive blanks in said mechanisms, the operation of said mechanisms being concurrent on the positioned blanks.
11. In apparatus for applying pintles to box parts and in combination, pintle-applying mechanism adapted to insert pintles by endwise movement of the pintle, mechanism for preparing the box part blank to receive the pintle, and blank feeding means for delivering a succession of blanks to said mechanism, said blank feeding means being operative to position successive blanks currently in said mechanisms, said mechanisms being connected to operate in unison, whereby concurrent operation is had on independent blanks.
12. In apparatus for applying pintles to box parts and in combination, pintle-applying mechanism, mechanism for preparing the box part blank to receive the pintle, and blank feeding means for delivering the blank to said mechanisms in predetermined succession, said feeding means including a carrier for supporting the blank through said mechanisms and movable to and from a normal position, and means for advancing the blank in such carrier.
13. In apparatus for applying pintles to box parts and in combination, pintle-applying mechanism, mechanism for preparing the box part blank to receive the pintle, and blank feeding means for delivering the blank to said mechanisms in predetermined succession, said feeding means including a carrier for supporting the blank through said mechanisms and movable to and from a normal position, and means for advancing the blank in such carrier, said advancing means being operative when the carrier is out of its normal position.
14. In apparatus for applying pintles to box parts and in combination, pintle-applying mechanism, mechanism for preparing the box part to receive the pintle, and blank feeding means for delivering the blank to said mechanisms in predetermined succession, said feeding means including a carrier for supporting the blank, said carrier being movable to position the blanks in a mechanism.
15. In apparatus for applying pintles to box parts and in combination, pintle-applying

- ing mechanism, mechanism for preparing the box part blank to receive the pintle, and blank feeding means for delivering the blank to said mechanisms in predetermined 5 succession, said feeding means including a carrier for supporting the blank, said carrier being movable toward and from a position to locate the blank in said mechanisms, and means operative when the carrier is out 10 of normal position for advancing the blank to locate it in position for carrier delivery to a mechanism.
16. In apparatus for applying pintles to box parts and in combination, pintle-applying mechanism, mechanism for preparing the box part blank to receive the pintle, and blank feeding means for delivering the blank to said mechanisms in predetermined 15 succession, said feeding means including a shiftable carrier support for the blank, means for introducing a blank to said carrier, and means for advancing the blank in said carrier to locate it in the successive mechanisms.
17. In apparatus for applying pintles to box parts and in combination, pintle-applying mechanism adapted to insert a pintle in a prepared box part blank, said mechanism including a shiftable support for the blank 20 during the applying operation, and blank feeding means for locating the blank opposite its support and for positioning it on and removing it from the support before and after the applying operation.
18. In apparatus for applying pintles to box parts and in combination, pintle-applying mechanism adapted to insert a pintle in a prepared box part blank, said mechanism including a shiftable support for the blank 25 during the applying operation, and means for positioning the blank on and removing it from the support, said means including a shiftable carrier for moving the blank.
19. In apparatus for applying pintles to box parts and in combination, pintle-applying mechanism adapted to insert a pintle in a prepared box part blank, said mechanism including a support for the blank during 30 the applying operation, and means for positioning the blank on and removing it from said support, said means including a carrier having a blank-receiving channel and shiftable toward and from a position to locate the blank on the support.
20. In apparatus for applying pintles to box parts and in combination, pintle-applying mechanism adapted to insert a pintle in a prepared box part blank, said mechanism including a support for the blank during 35 the applying operation, and means for positioning the blank on and removing it from said support, said means including a carrier having a blank-receiving channel and shiftable toward and from the position to locate the blank on the support, means for locating the 40 blank in said channel opposite said support while the carrier is out of such position.
21. In apparatus for applying pintles to box parts and in combination, pintle-applying mechanism adapted to insert a pintle in a prepared box part blank, said mechanism including a shiftable support for the blank during the applying operation, said pintle-applying mechanism including means for intermittently feeding pintle material 45 into applying position, means for completing the applying operation after the material has been positioned, and means for positioning the blank on and removing it from its support, said latter means including a carrier movable toward and from the pintle-applying position.
22. In apparatus for applying pintles to box parts and in combination, pintle-applying mechanism adapted to insert a pintle in a prepared box part blank, said mechanism including a support for the blank during 50 the applying operation, said pintle-applying mechanism including means for intermittently feeding pintle material into applying position, means for completing the applying operation after the material has been positioned, and means for positioning the blank on and removing it from its support, said latter means including a carrier movable toward and from the blank-applying position, and means for preventing pintle material feed in the absence of a properly located blank in the carrier.
23. In apparatus for applying pintles to box parts and in combination, pintle-applying mechanism adapted to insert a pintle in a prepared box part blank, said mechanism including a support for the blank during 55 the applying operation, a carrier for positioning the blank on and removing it from said support, said applying mechanism including means for feeding pintle material into applying position while the blank is on its support.
24. In apparatus for applying pintles to box parts and in combination, pintle-applying mechanism adapted to insert a pintle in a prepared box part blank, said mechanism including a support for the blank during 60 the applying operation, a carrier for positioning the blank on and removing it from said support, said applying mechanism including means for feeding pintle material into applying position while the blank is on its support, and means operative in the pintle material feed means for rendering said feed means inactive in the absence of a properly-positioned blank in the carrier.
25. In apparatus for applying pintles to box parts and in combination, pintle-applying mechanism adapted to insert a pintle in a prepared box part blank, said mechanism including a support for the blank during 65 the applying operation, a carrier for posi-

tioning the blank on and removing it from said support, said applying mechanism including means for feeding pintle material into applying position while the blank is on its support, said feed means including a pawl and ratchet mechanism operative to advance the pintle material, and means for rendering said pawl and ratchet mechanism inactive in the absence of a properly-positioned blank in said carrier.

26. In apparatus for applying pintles to box parts and in combination, pintle-applying mechanism adapted to insert a pintle in a prepared box part blank, said mechanism including a support for the blank during the applying operation, a carrier for positioning the blank on and removing it from said support, said applying mechanism including means for feeding pintle material into applying position while the blank is on its support, said feed means including a pawl and ratchet mechanism operative intermittently to advance the pintle material, and means for retaining the pawl and ratchet mechanism inactive in the absence of a properly-positioned blank in said carrier.

27. In apparatus for applying pintles to box parts and in combination, pintle-applying mechanism adapted to insert a pintle in a prepared box part blank, said mechanism including a support for the blank during the applying operation, a carrier for positioning the blank on and removing it from said support, said applying mechanism including means for feeding pintle material into applying position while the blank is on its support, said feed means including a ratchet, a pawl carrying member operative on the ratchet, a cam, and operative connections between the cam and said member, said connections including a normally-inactive lost motion structure.

28. In apparatus for applying pintles to box parts and in combination, pintle-applying mechanism adapted to insert a pintle in a prepared box part blank, said mechanism including a support for the blank during the applying operation, a carrier for positioning the blank on and removing it from said support, said applying mechanism including means for feeding pintle material into applying position while the blank is on its support, said feed means including a ratchet, a pawl carrying member operative on the ratchet, means including a lost motion structure for oscillating said member, and trip mechanism operative on said member for preventing member movements in the absence of a properly-positioned blank in the carrier.

29. In apparatus for applying pintles to box parts and in combination, pintle-applying mechanism adapted to insert pintles by endwise movement of the pintle, mechanism for preparing the box part blank with com-

plete pintle-receiving ears to receive the pintle, and blank feeding means for delivering the blank to said mechanisms in predetermined succession, said preparing means including a form for supporting the blank during the blank preparing operation, said feeding means being movable to position the blank on and remove it from said form.

30. In apparatus for applying pintles to box parts and in combination, pintle-applying mechanism, mechanism for preparing the box part blank to receive the pintle, said preparing mechanism including a form to support the blank during the preparing operation, said form having shaping-projections, and blank feeding means for positioning the blank on and removing it from the form, said means including a carrier for supporting the blank during blank movements and shiftable toward and from a position wherein the blank is supported on the form.

31. In apparatus for applying pintles to box parts and in combination, pintle-applying mechanism, mechanism for preparing the box part blank to receive the pintle, said preparing mechanism including a form to support the blank during the preparing operation, said form having shaping-projections, and blank feeding means for positioning the blank on and removing it from the form, said means including a carrier for supporting the blank during blank movements and shiftable toward and from a position wherein the blank is supported on the form, and means controlled by movements of the blank feeding means for positioning the blank relative to said projections.

32. In apparatus for applying pintles to box parts and in combination, mechanism for preparing the box part blank to receive the pintle and including a form to support the blank during the preparing operation, said form having shaping-projections, and blank feeding means for positioning the blank on and removing it from the form, said feeding means including a carrier for supporting the blank during its movements, said carrier being movable to position the blank on the form, means for positioning the blank in the carrier opposite the form, and means for moving the blank relative to the carrier to accommodate for said shaping-projections.

33. In apparatus for applying pintles to box parts and in combination, mechanism for preparing the box part blank to receive the pintle and including a form to support the blank during the preparing operation, said form having shaping projections, and blank feeding means for positioning the blank on and removing it from the form, said feeding means including a carrier for supporting the blank during its movements,

said carrier being movable to position the blank on the form, means for positioning the blank in the carrier opposite the form, and means for moving the blank relative to the carrier to accommodate for said shaping projections, said latter means being controlled by movements of said blank positioning means.

34. In apparatus for applying pintles to box parts and in combination, mechanism for preparing the box part blank to receive the pintle and including a form to support the blank during the preparing operation, said form having shaping projections, and blank feeding means for positioning the blank on and removing it from the form, said feeding means including a carrier for supporting the blank during its movements, said carrier being movable to position the blank on the form, means for positioning the blank in the carrier opposite the form, and means for moving the blank relative to the carrier to accommodate for said shaping projections, said latter means including an element pivotally supported on the carrier and having means for engaging a wall of the blank, and mechanism carried by the blank-positioning means for controlling the movements of said pivoted element.
35. In apparatus for applying pintles to box parts and in combination, mechanism for preparing the box part blank to receive the pintle and including a form to support the blank during the preparing operation, said form having shaping projections, and blank feeding means for positioning the blank on and removing it from the form, said feeding means including a carrier for supporting the blank during its movements, said carrier being movable to position the blank on the form, means for positioning the blank in the carrier opposite the form, and means for moving the blank relative to the carrier to accommodate for said shaping projections, said latter means including an element pivotally supported on the carrier and having means for engaging a wall of the blank, and a cam shaped element carried by and movable with the blank positioning means for controlling the movements of said pivoted element.

36. In apparatus for applying pintles to box parts and in combination, pintle-applying mechanism, mechanism for preparing the box part blank to receive the pintle and including a form having shaping projections, and blank feeding means for delivering the blanks to said mechanism in predetermined succession, said feeding means including a carrier on which the blank is supported during blank movements through said mechanisms and movable into and out of a normal position, blank-advancing means for shifting the blank on the carrier and for locating it therein in proper positions

relative to said mechanisms, and means for positioning the blank relative to said projections, said latter means including an element pivotally supported on the carrier and adapted to cooperate with a wall of the blank to shift the blank relative to the carrier, and means carried by the blank-advancing means for controlling the movements of said pivoted element.

37. In apparatus for applying pintles to box parts and in combination, pintle-applying mechanism, mechanism for preparing the box part blank to receive the pintle and including a form having shaping projections, and blank feeding means for delivering the blanks to said mechanism in predetermined succession, said feeding means including a carrier on which the blank is supported during blank movements through said mechanisms and movable into and out of a normal position, blank-advancing means for shifting the blank on the carrier and for locating it therein in proper positions relative to said mechanisms, and means for positioning the blank relative to said projections, said latter means including an element pivotally supported on the carrier and adapted to cooperate with a wall of the blank to shift the blank relative to the carrier, and a cam element carried by the blank advancing means for controlling the movements of said pivoted element.

38. In apparatus for applying pintles to box parts and in combination, pintle-applying mechanism, mechanism for preparing the box part blank to receive the pintle and including a form having shaping projections, and blank feeding means for delivering the blanks to said mechanism in predetermined succession, said feeding means including a carrier on which the blank is supported during blank movements through said mechanisms and movable into and out of a normal position, blank-advancing means for shifting the blank on the carrier and for locating it therein in proper positions relative to said mechanisms, and means for positioning the blank relative to said projections, said latter means including an element pivotally supported on the carrier and adapted to cooperate with a wall of the blank to shift the blank relative to the carrier, and a cam element carried by the blank advancing means for controlling the movements of said pivoted element.

39. In apparatus for applying pintles to box parts and in combination, pintle-applying mechanism, mechanism for preparing the box part blank to receive the pintle and including a form having shaping projections, and blank feeding means for delivering the blanks to said mechanism in predetermined succession, said feeding means including a carrier on which the blank is supported during blank movements through said mechanisms and movable into and out of a normal position, blank-advancing means for shifting the blank on the carrier and for locating it therein in proper positions relative to said mechanisms, and means for positioning the blank relative to said projections, said latter means including an element pivotally supported on the carrier and adapted to cooperate with a wall of the blank to shift the blank relative to the carrier, and an element carried by the blank advancing means and having a cam slot cooperating with said pivoted element to control the movements of the latter, said slot being operative to position the blank to permit free movements thereof relative to said projections when said blank-advancing mechanism is at its opposite extremes of movement, the slot configuration permitting shaping operations on the blank by the projections during travel of the blank-advancing means between its extremes of movement.

39. In apparatus for applying pintles to

box parts and in combination, pintle-applying mechanism adapted to insert pintles by relative movements of blank and pintle in the direction of length of the pintle, mechanism for preparing the box part blank with complete pintle-receiving ears to receive the pintle, each of said mechanisms including a form to support the blank while in such mechanisms, and blank feeding means for delivering the blank to said forms in predetermined succession.

40. In apparatus for applying pintles to box parts and in combination, pintle-applying mechanism, mechanism for preparing the box part blank to receive the pintle, each of said mechanisms including a form to support the blank while in such mechanisms, and blank feeding means for delivering the blank to said forms in predetermined succession, said means including a shiftable carrier for supporting the blank during blank movements and having recesses to receive said forms.

41. In apparatus for applying pintles to box parts and in combination, pintle-applying mechanism, mechanism for preparing the box part blank to receive the pintle, each of said mechanisms including a form to support the blank while in such mechanisms, and blank feeding means for delivering the blank to said forms in predetermined succession, said means including a carrier for supporting the blank during blank movements and having recesses to receive said forms, said carrier having members active in moving the blank from the forms.

42. In apparatus for applying pintles to box parts and in combination, pintle-applying mechanism, mechanism for preparing the box part blank to receive the pintle, each of said mechanisms including a form to support the blank while in such mechanisms, and blank feeding means for delivering the blank to said forms in predetermined succession, said means including a carrier for supporting the blank during blank movements and having recesses to receive said forms, said carrier having members active in moving the blank from the forms, said forms having configurations adapted to receive said members while the blank is positioned on the forms.

43. In apparatus for applying pintles to box parts and in combination, pintle-applying mechanism, mechanism for preparing the box part blank to receive the pintle, each of said mechanisms including a form to support the blank while in such mechanisms, and blank feeding means for delivering the blank to said form in predetermined succession, said means including a carrier for supporting the blank during blank movements and having recesses to receive said forms, said carrier having members active in moving the blank from the forms, said forms

having recesses complementary to said members to permit movements of the latter into and out of the form planes.

44. In apparatus for applying pintles to box parts and in combination, pintle-applying mechanism adapted to insert pintles by endwise movement of the pintle, mechanism for preparing the box part blank to receive the pintle, and blank feeding means for delivering the blank to said mechanism in predetermined succession, said means including a carrier for supporting the blanks during blank movements, and means for delivering blanks to said carrier in regular succession.

45. In apparatus for applying pintles to box parts and in combination, pintle-applying mechanism, mechanism for preparing the box part blank to receive the pintle, and blank feeding means for delivering the blank to said mechanisms in predetermined succession, said means including a shiftable carrier for concurrently supporting a plurality of blanks during blank movements, said mechanisms being operative concurrently on different blanks.

46. In apparatus for applying pintles to box parts and in combination, pintle-applying mechanism, mechanism for preparing the box part blank to receive the pintle, and blank feeding means for delivering the blank to said mechanisms in predetermined succession, said means including a shiftable carrier for concurrently supporting a succession of blanks during blank movements, said mechanisms being operative concurrently on succeeding blanks.

47. In apparatus for applying pintles to box parts and in combination, pintle-applying mechanism, mechanism for preparing the box part blank to receive the pintle, and blank feeding means for delivering the blank to said mechanisms in predetermined succession, said means including a shiftable carrier for concurrently supporting a plurality of blanks during blank movements, said mechanisms being operative concurrently on different blanks, and means for introducing a blank to said carrier concurrently with mechanism activity.

48. In apparatus for applying pintles to box parts and in combination, pintle-applying mechanism, mechanism for preparing the box part blank to receive the pintle, and blank feeding means for delivering the blank to said mechanisms in predetermined succession, said means including a shiftable carrier for concurrently supporting a plurality of blanks during blank movements, said mechanisms being operative concurrently on different blanks, and means for introducing a blank to said carrier, said introducing means being active to deliver a blank to the carrier during mechanism activity.

49. In apparatus for applying pintles to box parts and in combination, pintle-applying

- ing mechanism, mechanism for preparing the box part blank to receive the pintle, and blank feeding means for delivering the blank to said mechanisms in predetermined succession, said means including a shiftable carrier for concurrently supporting a plurality of blanks during blank movements, said mechanisms being operative concurrently on different blanks, and means for introducing blanks to said carrier, said introducing means including means for limiting blank introduction to a single blank and during mechanism activity.
50. In apparatus for applying pintles to box parts and in combination, a carrier for supporting the box part blank, means for successively preparing the blank to receive the pintle and for positioning the pintle in such prepared blank by endwise movement of the pintle while the blank is so supported, and means for introducing blanks individually to said carrier.
51. In apparatus for applying pintles to box parts and in combination, a shiftable carrier for supporting the box part blank, means for successively preparing the blank to receive the pintle and for positioning the pintle in such prepared blank while the blank is so supported, and means for introducing blanks individually to said carrier, said introducing means including a blank-collecting conveyer, and means for releasing blanks individually from said conveyer and for delivering the released blank to the carrier.
52. In apparatus for applying pintles to box parts and in combination, a shiftable carrier for supporting the box part blank, means for successively preparing the blank to receive the pintle and for positioning the pintle in such prepared blank while the blank is so supported, and means for introducing blanks individually to said carrier, said introducing means including a blank-collecting device, and mechanism for releasing blanks from said device in regular succession and for advancing the released blank into the carrier.
53. In apparatus for applying pintles to box parts and in combination, a carrier for supporting the box part blank, means for successively preparing the blank to receive the pintle and for positioning the pintle in such prepared blank while the blank is so supported, and means for introducing blanks individually to said carrier, said carrier being movable toward and from a normal position, said introducing means comprising a blank storage device, and means for intermittently releasing blanks from said device in regular succession and for advancing the released blank to said carrier, activity of said releasing means being limited to periods when the carrier is in normal position.
54. In apparatus for applying pintles to box parts and in combination, a shiftable carrier for supporting the box part blank, means for successively preparing the blank to receive the pintle and for positioning the pintle in such prepared blank while the blank is so supported, and means for introducing blanks individually to said carrier, said introducing means including a conveyer, stop mechanism adapted to restrain movements of blanks over said conveyer, and means for intermittently operating said stop mechanism to release the advance blank from said conveyer.
55. In apparatus for applying pintles to box parts and in combination, a carrier for supporting the box part blank, means for successively preparing the blank to receive the pintle and for positioning the pintle in such prepared blank while the blank is so supported, and means for introducing blanks individually to said carrier, said carrier being movable toward and from a normal position, said introducing means including a conveyer positioned in alignment with the normal position of the carrier, and mechanism for normally restraining blanks from movement into the carrier, said mechanism being operative to release a single blank and advance it to the carrier when the latter is in normal position.
56. In apparatus for applying pintles to box parts and in combination, a shiftable carrier for supporting the box part blank, means for successively preparing the blank to receive the pintle and for positioning the pintle in such prepared blank while the blank is so supported, and means for introducing blanks individually to said carrier, said introducing means including a stop mechanism normally extending into the path of travel of an advancing blank and adapted to restrain the blank from entering the carrier, a blank advancing mechanism for advancing a blank into the carrier, said stop and advancing mechanisms being co-related in operation to provide release of a blank when the advancing mechanism is in position to advance the released blank into the carrier.
57. In apparatus for applying pintles to box parts and in combination, a shiftable carrier for supporting the box part blank, means for successively preparing the blank to receive the pintle and for positioning the pintle in such prepared blank while the blank is so supported, and means for introducing blanks individually to said carrier, said introducing means including a stop mechanism normally extending into the path of travel of an advancing blank and adapted to restrain the blank from entering the carrier, a blank advancing mechanism for advancing a blank into the carrier, and complementary means in said stop and advance mechanisms adapted to cooperate

to move the stop mechanism to release a blank at a predetermined point in the travel of the advancing mechanism.

58. In apparatus for applying pintles to box parts and in combination, a carrier for supporting the box part blank, means for successively preparing the blank to receive the pintle and for positioning the pintle in such prepared blank while the blank is so supported, and means for introducing blanks individually to said carrier, said introducing mechanism including a pivoted stop member normally extending into the path of an advancing blank, a reciprocating blank advancing member, and means carried by said member and operative on the stop member for moving the latter out of restraining position when the advancing member is at a predetermined point in its reciprocating movement.

59. In combination, a carrier for supporting a plurality of spaced-apart box part blanks and in which the blanks are advanced flatwise, means for moving said carrier to and from a normal position, said movements being transverse to the direction of blank advance movement, means for advancing the blanks step by step while the carrier is out of such normal position, and work-performing mechanism having a blank supporting form extending into the carrier when the latter is in normal position, movement of the carrier to its normal position locating the blank on said form.

60. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, and pintle-applying mechanism having a blank supporting form extending into the path of travel of the blanks when the carrier is in normal position, movement of the carrier to such normal position locating the blank on said form.

61. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, and blank-preparing and pintle-applying mechanisms each having a blank-supporting

form extending into the travel path of blanks on the carrier when the latter is in normal position, said forms being located at successive points intermediate the ends of the carrier, movement of the carrier to its normal position locating a blank on each of said forms.

62. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, and blank-preparing and pintle-applying mechanisms, each having a blank-supporting form extending into the travel path of blanks on the carrier when the latter is in normal position, said forms being located at successive points intermediate the ends of the carrier, movement of the carrier to its normal position locating a blank on each of said forms, and means rendered active by the movements of the blank-advancing means for shifting the position of a blank relative to the carrier during movements of the latter to and from its normal position.

63. In combination, a carrier for supporting a plurality of spaced-apart box part blanks and in which the blanks are advanced flatwise, means for moving said carrier to and from a normal position, said movements being transverse to the direction of blank advance movement, means for advancing the blanks step by step while the carrier is out of such normal position, and work-performing mechanism having a blank supporting form extending into the carrier when the latter is in normal position, movement of the carrier to its normal position locating the blank on said form, movements of the carrier and of the blank-advancing means being non-concurrent.

64. In combination, a carrier for supporting a plurality of spaced-apart box part blanks and in which the blanks are advanced flatwise, means for moving said carrier to and from a normal position, said movements being transverse to the direction of blank advance movement, means for advancing the blanks step by step while the carrier is out of such normal position, and work-performing mechanism having a blank supporting form extending into the carrier when the latter is in normal position, movement of the carrier to its normal position locating the blank on said form, movements of the carrier and blank-advancing means being non-concurrent, advancing movements of the advancing means being limited to

periods between successive movements of the carrier from and to its normal position.

65. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, said instrumentality having a plurality of spaced projections adapted to intersect the blank travel path when the carrier is out of its normal position, said projections providing spaces to receive individual blanks during the advancing movements, and work-20 performing mechanism having a blank supporting form extending into the carrier when the latter is in normal position, movement of the carrier to its normal position locating the blank on said form.

25. 66. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, said instrumentality having a plurality of spaced projections adapted to coöperate with the carrier during blank advancing movements, said projections being out of the flatwise 40 planes of the blanks when the carrier is in normal position and intersecting such planes when the carrier is out of such position, and work-performing mechanism having a blank supporting form extending into the carrier 45 when the latter is in normal position, movement of the carrier to its normal position locating the blank on said form.

67. In apparatus for applying pintles to box parts and in combination, a carrier for supporting a succession of spaced-apart part blanks and in which the blanks are advanced flatwise, means for moving said carrier to and from a normal position with the movements transverse to the direction of blank 50 advance, a blank advancing instrumentality operative relative to the carrier when the latter is out of normal position for advancing the blanks step by step, a stationary element having spaced projections intersecting flatwise planes of the blanks when the carrier is in normal position, said advancing instrumentality having projections opposing said element projections, said instrumentality projections being out of such blank

planes when the carrier is in normal position and extending into such planes when the carrier is out of its normal position, and work-performing mechanism having a blank supporting form extending into the carrier when the latter is in normal position, movement of the carrier to its normal position locating the blank on said form. 65

68. In apparatus for applying pintles to box parts and in combination, a carrier for supporting a succession of spaced-apart box part blanks and in which the blanks are advanced flatwise, means for moving said carrier to and from a normal position with the movements transverse to the direction of blank advance, a blank advancing instrumentality operative relative to the carrier when the latter is out of normal position for advancing the blanks step by step, said advancing instrumentality being positioned at one side of said carrier and having spaced-apart projections adapted to extend into said carrier, a stationary element at the opposite side of the carrier and also having projections adapted to extend into the carrier in opposition to the instrumentality 85 projections, movements of the carrier into and out of its normal position rendering said sets of projections successively active as spacing element for the blanks, and work-performing mechanism having a blank supporting form extending into the carrier when the latter is in normal position, movement of the carrier to its normal position locating the blank on said form. 90

69. In apparatus for applying pintles to box parts and in combination, blank preparing mechanism, pintle-applying mechanism, said mechanisms being positioned to operate successively on a box part blank, a carrier for supporting a plurality of blanks and movable into and out of a normal position, means operative to locate blanks at predetermined stations of the carrier when the carrier is out of its normal position, said blank preparing and pintle-applying mechanisms being located in the path of travel of the blanks of different stations of the carrier, whereby movement of the carrier to its normal position will locate blanks in said mechanisms. 100 105 110

70. In apparatus for applying pintles to box parts and in combination, a carrier for supporting a plurality of box part blanks in independent stations on the carrier, said carrier being movable from and to a normal position, blank preparing and pintle-applying mechanisms located to be operative at successive stations of the carrier when the latter is in such normal position, and instrumentality for advancing blanks from station to station while the carrier is out of such normal position, movements of the carrier being in directions transverse to the ad- 120 125

vancing movements of the blanks, whereby independent blanks will be concurrently positioned in said mechanisms and a blank will be positioned successively in the mechanisms.

71. In apparatus for applying pintles to box parts and in combination, a carrier for supporting a plurality of box part blanks in independent stations on the carrier, said carrier being movable from and to a normal position, blank preparing and pintle-applying mechanisms located to be operative at successive stations of the carrier when the latter is in such normal position, means for introducing a blank to one of said stations while the carrier is in such normal position, and an advancing instrumentality operative to advance the positioned blanks from station to station when the carrier is out of its normal position.

72. In apparatus for applying pintles to box parts and in combination, a carrier for

supporting a plurality of box part blanks in independent stations on the carrier, said carrier being movable from and to a normal position, blank preparing and pintle-applying mechanisms located to be operative at successive stations of the carrier when the latter is in such normal position, means for introducing a blank to one of said stations while the carrier is in such normal position, and an advancing instrumentality operative to advance the positioned blanks from station to station when the carrier is out of its normal position, movements of the carrier being transverse to the direction of advance of the blanks.

In testimony whereof I have hereunto set my hand in presence of two subscribing witnesses.

HENRY HERMANI.
